UNITED STATES PATENT OFFICE.

PERCY A. E. ARMSTRONG, OF LOUDONVILLE, NEW YORK.

ELECTRICAL FURNACE AND REMOVABLE HEATING UNIT THEREFOR.

Application filed March 25, 1920. Serial No. 368,519.

To all whom it may concern:

Be it known that I, Percy A. E. Armstrong, a subject of the King of Great Britain, and residing at Loudonville, in the county of Albany, State of New York, have invented certain new and useful Improvements in Electrical Furnaces and Removable Heating Units Therefor, of which the following is a specification.

10 My invention relates to electrical furnaces and removable heating units therefor.

One of the objects of my invention is the provision of insulated electrical heating elements for furnaces and the like which can be readily taken out and replaced or renewed, as occasion may arise therefor, thus enabling individual burnt out heating elements to be replaced quickly and readily and with a minimum of interference with 20 the use of the furnace.

Another object of the invention is the provision of the heating elements with insulating means, serving also as heat storing means, made up in sections and adapted to 25 keep the elements in proper position and out of contact with one another. A preferable mode of attaining this object is by providing perforated blocks or bricks of refractory material, such as alundum, which 30 is heat resistant and is not readily frangible at the high temperatures employed, with the heating elements extending through such perforations. When the heating elements 35 are of "hair-pin" formation, which is the form commonly used, the bricks of alundum, or the like material, may each be provided with a pair of holes or passages arranged substantially parallel to one another and through which the two branches of the heating 40 element may extend, or separate bricks may be provided for each side member. Instead of using separate bricks, or sections of the insulating material, same may be cast or otherwise formed so as to extend for substantially the entire length of the heating 45 element.

Other objects of my invention will appear in connection with the following description.

50 In the accompanying drawings Fig. 1 is a view in perspective, with parts broken away, of one form of furnace making use of my invention. Fig. 2 is a cross-sectional view of a circular furnace. Fig. 3 is a cross-sectional view of an insulated heating unit. Fig. 4 is a part sectional view of a plurality

of protected heating elements connected in series. Fig. 5 is an isometrical view showing two forms of insulating bricks. Fig. 6 is a cross-sectional view of a vertical furnace. Figs. 7 and 8 are detail modifications of parts of the vertical furnace. Figs. 9, 10 and 11 are cross-sectional views of modified forms of insulated heating units, and Figs. 12 and 13 are cross-sectional views of circular furnaces of modified form.

I have illustrated heating elements 10 of the familiar hair-pin form. Blocks or bricks perforated for the passage of the heating element are provided, of alundum, 70 or other refractory insulating material, adapted to withstand high heat without being readily broken. Alundum is a good material for this purpose, but other materials having similar properties may be 75 used. The bricks may be of various forms. For example, the bricks may be of the flat-sided type, as shown at 11, or of interlocking type 11' with recesses 13 on one side and corresponding projections 14 on the opposite side, adapted to be nested in the recesses 13. The bricks may be of sufficient length to have two parallel passages 15, 15 formed therein and adapted to receive both side members 10' of the elements 10, or 80 single bricks 11'' may be provided with single passages 15' for each of the side members 10', and such bricks 11'' may be used on the connecting or base portion 10'' of the heating element, if desired. Where the 90 bricks with two holes are used, the base portion 10'' of the heating elements may be received in recesses 16 of hollowed out bricks 17, if desired, such end bricks 17 being preferably put into place after insertion 95 in the furnace of the removable heating units, comprising the heating element 10 with bricks such as 11, 11', 11'', or insulating material of other forms, in place thereon, and designated generally by reference 100 character 18.

The protected or insulated units 18, made up of the heating elements 10 in the form of wires, bars, rods, and the like, with the bricks strung thereon, or, in other words, 105 consisting of a series of the bricks with the openings therein aligned and the heating elements passing through the passages thus provided, may be made use of in various ways and relations. For example, to give 110 a simple instance, one or more of such units may be laid on the ground or on a concrete

floor and used for heating pots or the like, placed thereon, and the invention includes the provision of such protected units for the purpose of heating in any way. Such protected units are preferably made use of, however, in electrical furnaces. Such furnaces may be of various kinds. For example, the invention may be used to advantage in furnaces for heat treating and annealing of metallic articles, and such furnaces are illustrated herein, but without limitation of the invention thereto.

In Fig. 1 is shown a furnace of a form used for heat treatment of metallic products, such as tool steel and the like.

The inner shell or lining 20 may be of clay or other suitable heat resisting material, but preferably is made of metallic material adapted to withstand high heat without substantial oxidation, corrosion and the like. For example, I preferably use stable surface alloy steel, as described in my Patent No. 1,322,511, granted November 25, 1919, which is well adapted for this purpose.

The shell 20 is surrounded by a second shell 21, which may be of similar material to shell 20, leaving an intermediate space 22 for the reception of the heating units 18 described above. The space outside the shell 21 and in rear of shell 20 is packed with suitable insulating material 22' and the whole enclosed in a suitable jacket 23.

Provision is made for inserting and removing the heating units 18 separately or singly.

The ends 10^a of the side portions 10' of elements 10 may extend through openings 24 in the back plate 25, being insulated therefrom by insulating sleeves 26, and may be connected up electrically in any desired way, as by means of lugs 27 (Fig. 4). Series connection is illustrated for simplicity, but any desired arrangement may, of course, be used. Lugs 27 may be attached by screws, or otherwise, so as to be readily connected and disconnected.

In the form shown the units 18 are removed and replaced from the front end of the furnace, the front plate 28 being made removable for this purpose.

When replacement is to be made, as for example, of a burnt out element, the plate 28 is removed, the corresponding lugs 27 disconnected, and the unit withdrawn and a new one inserted in its place, and the parts replaced as before. When other units are supported on the one desired to be replaced, it may be necessary when removing same to let the supported units move down one space and insert the new unit at the top, which can easily be done. The end brick 17 is preferably put in place last after the unit is in place. Removal and replacement may be facilitated by making plate 28 in several parts, if desired.

The furnace doors should preferably be of such design that they can be readily removed to give access to plate 28. In the form shown the doors 29, 29 are slidably supported on guide rod 30 and kept in place by slide-way 31 and are opened by the operator stepping on pedal 32, which is connected by link 33 to the counterweighted lever 34 from the opposite arms whereof links 35 and 36 run to the doors. When the foot is removed from pedal 32, the doors are automatically closed by the counterweight. Links 35 and 36 preferably have a pin and slot connection with the doors so that they may be readily disconnected.

The invention may be applied to furnaces of various types as square, rectangular, elliptical, round, etc., etc. In Fig. 2 a cross section of a round furnace is shown, the inner shell 20' of which is provided with ribs 20^a, whereby it is spaced from the surrounding shell 21', and trays 37, 38 are provided for the reception of annealing boxes and the like. These trays are preferably of the same material as the inner shell and it is to be noted that when annealing boxes and the like are pushed in, moved around, and pulled out, it is of great advantage to have the furnace base or shelves of the alloy steel described, which is not gouged or broken out thereby, as commonly happens with furnaces made of clay or the like materials.

Heating units are removed and replaced in the circular furnaces in the manner already described, any units supported by the one removed, being permitted to move down a space and the new element inserted at the top of the quadrant or other division.

In Fig. 9 I have illustrated a heating element provided with bricks 11" having one hole each for receiving the side member 10' of heating elements 10. The heating unit of Fig. 10 is similar to that of Fig. 9, but instead of bricks the insulating means is formed in a single piece 11^a, for each side member of the heating element, which may be cast in place on the heating element or separately formed, and the element inserted therein. In Fig. 11 I have shown a single insulating member 11^a, through which both side members of the heating element extend,

Fig. 12 shows a modified form of furnace making use of heating units comprising bricks 11", as shown in Fig. 9. In this form the shell 20^a is provided with alternate, preferably integrally cast, ribs 40 and intermediate recesses 41 having the bottoms 42 thereof rounded or otherwise formed so that the insulating means such as bricks 11" of the heating units can fit closely therein. Removal and replacement of these units is accomplished in the manner already described, but the replacement unit is always put back into the same place as the one taken out.

The bricks 11" may be placed around the

base portion 10" of the heating element 10, as shown in Figs. 9, 10 and 13, or, if desired, same may be dispensed with at the base of the heating element, so long as same does not come into contact with conducting surfaces.

The furnace of Fig. 13 is similar to that of Fig. 12, but ribs 40' of shell 20^a thereof are shorter, and the shell 21^a is spaced a proper distance from shell 20^a by suitable spacing means, as indicated at 43.

The constructions shown in Figs. 12 and 13 enable the heating element to be placed substantially close to the inner wall of the shell lining, giving efficient heating results, but, nevertheless, the metallic lining material has sufficient mass to hold heat for considerable periods and to secure gradual heating and cooling of the furnace which is desirable, for example, in annealing.

In Fig. 6 I have shown a vertical cylindrical furnace 45 such as used, for example, in gun shops.

The protected units 18' are arranged in banks 46, 46 about the interior of the furnace walls. They may be supported in various ways, as, for example, on projecting bricks 47, as shown in Figs. 6 and 7, or by means of studs 48 of heat resisting material or metal set in the furnace wall and received in loops 10^b of the heating elements 10, with the insulating sleeve 49 of alundum or the like material interposed therebetween.

While I have shown certain forms of apparatus in which my invention may be embodied, it will be understood that same are only for illustrating the invention and affording a clear understanding thereof and are not to limit the invention.

I claim:

1. A unitary electrical heating unit comprising a plurality of insulating, heat resisting bricks each having a pair of parallel aligned apertures, and an electrical heating element of hair-pin form extending within the passages so formed, such unit being adapted to be separately inserted in or removed from a heating device such as a furnace or the like.

2. As a new article of manufacture, a unitary heating element for electrical heating comprising a plurality of heat resistant bricks each provided with a hole, and a strong metallic electrical heating element extending through said holes, said heating element being complete in itself and adapted to be bodily inserted in or removed from a furnace or like heating device.

3. An electric furnace having a chambered wall, and heating units comprising strong metallic electrical heating elements and insulating members strung thereon, said units being removably and replaceably received within the chamber in the furnace wall.

4. An electric furnace having a chamber

in the wall and a lining separating the chamber from the interior of the furnace, a removable closure for the chamber, and unitary electrical heating units comprising strong metallic electrical heating elements and insulating members strung thereon and adapted to be separately inserted and removed through the opening provided by the removal of said closure.

5. An electric furnace comprising a chambered wall, a removable closure for the chamber in the forward end thereof, and a series of heating units comprising heating elements and insulating members strung thereon and said units being adapted to be removed one by one through the opening in the front of said furnace provided by the removal of said closure.

6. An electric furnace comprising an interior lining member and a chamber about said lining member extending lengthwise of the furnace a removable closure for said chamber at one end of said furnace and a plurality of heating units comprising electrical heating elements and insulating means received within said chamber and said heating units being adapted to be withdrawn one by one from said chamber through the opening provided by removal of said closure.

7. In an electric furnace, a lining shell, a heating element chamber extending substantially around said shell, a series of separate heating units adapted to be removably received in said chamber and comprising electrical heating elements of hair-pin form and insulating members strung thereon and arranged substantially parallel to the longitudinal axis of the furnace, said units being separately removable from said chamber.

8. In an electric furnace, a lining of heat resistant alloy steel and a series of unitary electrical heating elements surrounding said lining and each adapted to be separately inserted or removed in the direction of its length.

9. In an electric furnace, a lining shell of heat resisting metallic material, a series of separate unitary heating units surrounding said lining and extending substantially parallel to the longitudinal axis thereof, said heating units comprising electrical heating elements and insulating members strung thereon, the upper heating units in the series being adapted to rest upon and be supported by those below.

10. In an electric furnace, a lining of heat resisting metallic material, a series of longitudinally removable unitary heating units arranged substantially to surround said lining, said heating units comprising heating elements and insulating members strung thereon, the heating elements lower down in the furnace serving to support those arranged thereabove, whereby when one of the lower-down heating units is removed, the

- heating units above the same are moved downward and a replacement element may be inserted at the top of the series.
11. In an electric furnace, a lining of 5 heat resistant metallic material, a series of longitudinally removable heating units arranged about the lining, said units comprising electrical heating elements of hair-pin form and insulating members strung there- 10 on, the base or connecting portion of the hair-pin heating elements being directed toward the front of the furnace and a removable closure for the heating element spaces arranged at the front of the furnace 15 and adapted, upon its removal, to permit the withdrawal from the forward end of the furnace of said heating elements in unitary form.
12. In an electric furnace, a lining of 20 heat-resisting metallic material, said lining being provided on its exterior with a series of grooves separated by intermediate ribs, and heating units, arranged about the lining and comprising electrical heating ele- 25 ments and insulating members strung thereon and of a form adapted to be received and fitted in said grooves.
13. An electric furnace comprising a heat- 30 resisting metallic lining having a series of grooves formed in the exterior wall thereof and arranged substantially parallel to the longitudinal axis of the lining, said grooves being arranged in pairs with intermediate ribs therebetween, and a series of heating 35 units comprising electrical heating elements of hair-pin form and insulating members strung thereon and adapted to be received
- within said grooves, and a removable closure at the end of said furnace adjacent to the base or connecting portion of said hair-pin heating elements, whereby, upon removal of said closure, said heating units may be longitudinally withdrawn for repair or replacement. 40
14. In an electric furnace, a lining of heat-resisting metallic material provided with grooves in its outer surface, and hair-pin electrical heating elements, the separated side portions thereof being provided with insulating members arranged thereon, said 45 heating units being adapted to be arranged about said lining with the insulating members received within said grooves. 50
15. In an electric furnace, a lining shell of heat-resisting material, a shell of similar material surrounding said lining and spaced therefrom to provide an intermediate chamber, a plurality of heating units comprising electrical heating elements of hair-pin form, and perforated bricks of heat-resisting and 60 insulating material strung thereon and having the separated ends of the side portions of such hair-pin heating elements projecting separately from the furnace at one end for the attachment of electrical connections, 65 and a removable closure for the chamber between said shells at the opposite end of said furnace, whereby said heating units may be removed and replaced by longitudinal movement through the opening left by 70 the removal of said closure.

In witness whereof, I have signed my name hereto.

PERCY A. E. ARMSTRONG.
